UNITED STATES PATENT OFFICE.

JOHN M. BEADLES, OF LOS ANGELES, CALIFORNIA.

FOUNTAIN PEN.

Application filed February 15, 1923. Serial No. 619,105.

To all whom it may concern:

Be it known that I, JOHN M. BEADLES, a citizen of the United States, residing at Los Angeles, in the county of Los Angeles 5 and State of California, have invented new and useful Improvements in Fountain Pens, of which the following is a specification.

This invention relates to fountain pens and more particularly to means for replenishing the exhausted pen.

It is an object of the present invention to provide a fountain pen including a flexible ink sack into which ink may be readily drawn by a siphonic action. Another object is to provide a sack filling device of extreme simplicity and few parts. Another object is to provide an ink sack having formed therewith and projecting from one end thereof a stud or lug adapted to be gripped 15 by a means for twisting the sack, the stud or lug being an integral part of the sack.

Other objects and advantages will be made manifest in the following specification of an embodiment of the invention illustrated in 25 the accompanying drawings, wherein

Figure 1 is a side elevation of a fountain pen incorporating the present improvement.

Fig. 2 is a sectional view of the barrel of the pen and a side elevation of the sack 30 twisting device removed therefrom; the sack being shown in the barrel in side elevation.

Fig. 3 is a sectional view showing the sack and the twisting device in assembled free relation in the barrel.

Fig. 4 is a longitudinal section showing the sack twisting device partially drawn out and showing the sack twisted thereby.

Fig. 5 is a clutch end view of the twisting device.

The invention is shown as embodying a flexible elastic sack or bag 2 which may be made of pliant rubber to be telescoped in a fountain pen barrel 3 having the usual spoon and pen elements as shown in Figure 1. One 45 end of the ink sack 2 is shown as provided with a shoulder 4 beyond which projects an axial stud 5 which is shown as solid to provide a body to be gripped by means by which the sack 2 may be twisted and thus 50 collapsed as shown in Figure 4 to expel air.

The sack twisting means is shown as including a small knob or button, this having a roughened periphery which may have a diameter about equal to the diameter of the 55 barrel 3. The knob has a threaded body

portion 7 to screw into internal threads 8 in the barrel with such a degree of friction as to prevent looseness of the knob so that it will remain put in any desired position. The inner end of the knob 6 is shown as provided 60 with a plurality of gripping jaws or prongs 9 which may be formed by bifurcating the knob radially inwardly from its inner end. The gripping jaws in their free position have diverging inclined faces 10 with slightly rounded shoulders 11 so that when the knob is applied to the threaded end of the barrel the gripping jaws 9 will be crowded inwardly or contracted so as to pass in under a shoulder 12 formed in the barrel 3 and 70 which has a conical bore or seat 13 expanding inwardly as to the end of the barrel. Thus when the knob 6 is applied the prongs 10 are adapted to yield when pushed past the annular shoulder 12 and will thus expand to their normal position as they engage 75 the conical seat 13.

After the knob 6 has been screwed in the ink sack 2 may then be inserted in the opposite end of the barrel 3 and the axial stud 80 5 will pass into the open clutch jaws.

When it is desired to refill the sack 2 it is only necessary to turn the knob 6 so that it will screw outwardly and this movement will result in the inward movement or contraction of the several clutch jaws 9 so that they will engage and bite into the stud 5 with sufficient pressure and friction to cause the stud to be rotated with the rotation of the knob 6. Since the opposite end of the 90 sack is connected to a fixed spoon it will be seen that the sack will be helically twisted as shown in Figure 4 and the air will be expelled. It is desirable to prevent the entire removal of the knob 6 outwardly from 95 the barrel while it is in engagement with the sack plug 5 and this limitation of movement is secured when the shoulder 4 of the sack moves into abutment, after a limited initial movement, with the wall forming the 100 seat 13 which is of less diameter than the diameter of the shoulder 4.

If desired the inner effective gripping faces of the jaws 9 may be toothed or roughened as at 9^a to secure a firm hold of the sack 105 plug or shank 5. Also, if desired, the shank may be provided with a slight peripheral groove or channel 5^a the surface of which will be engaged by inwardly projecting contiguous faces of the jaws 9.

Obviously, as the sack is untwisted and expands the void will be filled by the inward flow of ink.

Preferably, the stud 5 is formed as an integral part of the rubber ink sack 2 and may be so treated as to give it a desired degree of hardness, as for instance by vulcanizing.

Further embodiments, modifications and variations may be resorted to within the spirit of the invention as here claimed.

What is claimed is:

1. In a fountain pen, a barrel, an ink sack insertable into one end of the barrel and having an integral reduced lug at one end, and a socket means mounted at the opposite end of the barrel and adapted to grip said lug of the sack and to turn the same so as to twist the sack said socket means consisting of a rotary split clutch.

2. In a fountain pen, a barrel, an ink sack insertable into one end of the barrel, and a socket means turnably mounted in the opposite end of the barrel and adapted to grip a portion of the sack and to turn the same so as to twist the sack; the said sack and said means being normally wholly free of each other.

3. In a fountain pen, a barrel, an ink sack insertable into one end of the barrel and having a lug at one end, and means mounted at the opposite end of the barrel and adapted to grip a portion of the sack and to turn the same so as to twist the sack, said means including contractive clutching jaws operative to contract on the lug part of the sack.

4. In a fountain pen, a barrel having an internal tapering seat, an ink sack insertable into one end of the barrel and having a lug and means mounted in one end of the barrel having yieldable clutch prongs engaging said seat whereby upon a relative longitudinal movement of said elements as to the seat they will contract and engage said lug and turn the same with a turning movement of said means to twist the sack.

5. In a fountain pen, a barrel having an

internal conical seat, an ink sack insertable into one end of the barrel and having a lug and a rotary socket mounted in one end of the barrel having yieldable clutch elements engaging said seat whereby upon a relative longitudinal movement of said elements as to the seat they will contract upon said lug and turn the same with a turning movement of said means to twist the sack.

6. In a fountain pen, a barrel having at one end a conical seat, a unitary member having a part threaded into said end of the barrel and having a set of yieldable jaws with outer inclined faces engaging said seat, whereby when the said member is screwed in one direction the jaws are contracted, and an ink sack, in said barrel, having a part encompassed by the jaws and engaged and rotated thereby when they are contracted.

7. In a fountain pen, an ink sack formed of flexible material, and having at one end an integral head with a reduced lug integral with the head, and socket means adapted to grip said lug and to turn the same so as to twist the sack, said socket means consisting of a rotary split clutch.

8. In a fountain pen, an ink sack formed of flexible material and having at one end an integral head with a reduced lug integral with the head, and socket means adapted to grip said lug and to turn the same so as to twist the sack, said socket means consisting of a rotary split clutch, including contractive clutching jaws operative to contract on said lug.

9. Operating means for a self filling fountain pen comprising, a spring member formed with sack engaging ends and means for compressing said member whereby said sack engaging ends will engage the ink sack of the pen in a manner to permit the sack to be operated to fill or expel the contents of the same for the purpose specified.

In testimony whereof I have signed my name to this specification.

JOHN M. BEADLES.
